ATTORNEY.

UNITED STATES PATENT OFFICE.

EMERY M. McVICKER, OF MILWAUKEE, WISCONSIN, ASSIGNOR TO J. F. McVICKER, OF MILWAUKEE, WISCONSIN.

RAIL-ANCHOR TIE PLATE.

Application filed April 11, 1925. Serial No. 22,246.

This invention relates to rail anchor tie plates.

One object of the present invention is the provision of a simple, yet effective, form of 5 rail anchor tie plate capable of economical construction.

Other objects and advantages will appear from the following description of two embodiments of the invention.

10 In the drawings:

Figure 1 is a plan view of a rail anchor tie plate constructed in accordance with the present invention.

Figure 2 is a sectional view taken substantially on the line 2—2 of Figure 1.

Figure 3 is a perspective view of a rail clamp.

Figure 4 is a modified form of the tie plate shown in Figures 1 and 2.

20 The rail anchor tie plate shown in Figures 1 and 2 is formed from a substantially rectangular heavy steel plate 10. Diagonal corners of the plate are struck up and sheared from the body of the plate along lines 11, 25 the tangs thus formed being bent over to form hooks 12, arranged to overhang the base flanges 13 of the rail. Substantially opposite each hook 12 the plate is punched to form spike receiving openings 14 adjacent 30 the rail flange and additional holes 15 are punched in the rear of the openings 14 for a purpose which will later appear.

35 In applying the tie plate to a rail it is first placed beneath the rail in a diagonal position so that the hooks 12 clear the base flanges, then lifted against the bottom of the rail and turned into the position shown so that the hooks 12 engage over the flanges, and then slide along the rail into the desired position on the tie 16. It may then be secured to the tie by driving spikes 17 through the openings 14 with the heads of the spikes engaging over the flanges. Wedges 18 may be driven into position between the 40 edges of the rail and the shanks of the spikes to firmly bind the rail against creeping.

45 In some instances, I prefer to use one or more clamps associated with one or both of the spikes to afford a firmer grip on the rail. In Figures 1 and 2 a clamp 19, such as shown in detail in Figure 3, has been employed. This clamp is shaped to provide a jaw 20 at one end, adapted to engage over a base flange 50 of a rail, and a depending lug 21 at the other

end adapted to engage in one of the holes 15 in the tie plate. A spike receiving opening 22 is formed through the body of the clamp, and shoulders 23 are formed in front of the opening 22 beneath the jaw 20. This clamp is ordinarily applied, as indicated in Figures 1 and 2, with the lug 21 in the opening 15 and the jaw 20 engaged over the rail flange, and a spike is driven through the opening 22 in the clamp, and the opening 14 in the tie plate, and into the tie. A wedge 18 is then driven into position between the edge of the rail and the shoulders 23 of the clamp. The rail is thus firmly held against creeping and side thrusts thereon are transmitted through the clamp and sustained by the engagement of the lug 21 with the rear wall of the opening 14.

55 As a further precaution against creeping additional wedges, such as shown at 25, may be driven into position between the hooks 12 and the top of the rail flange. In this instance, each hook 12 is grooved as at 26, to provide an appropriate seat for the wedge.

60 The tie plate shown in Figure 4 is similar to that just described, except that both hooks 12' are disposed at one side of the rail, the other side of the rail being retained in position by the spikes 17' and a similar clamp 19'.

65 Various changes may be made in the embodiment of the invention hereinabove described, without departing from or sacrificing any of the advantages of the invention as defined in the appended claims.

70 I claim:

1. In a rail anchor tie plate the combination of a tie plate having an integral hook portion for engagement over a base flange of a rail, a spike opening through said plate adjacent the opposite flange of a rail, a spike in said opening, and a wedge between said spike and flange to prevent creeping of the rail.

75 2. In a rail anchor tie plate the combination of a tie plate having integral thrust sustaining abutment means engaging a base flange of a rail, a spike opening through said plate adjacent the other base flange of the rail, a spike in said opening, and a wedge between said spike and flange to prevent creeping of the rail.

80 3. In a rail anchor tie plate the combination of a tie plate having integral abutment means for sustaining side thrusts of a rail,

spike openings through said plate adjacent the base of said rail, a spike through one of said openings, a wedge between said spike and rail, a clamp overlying another of 5 said openings, a spike thru said clamp and last named opening, said clamp being interlocked with said tie plate and having a jaw overlying a base flange of a rail, a thrust sustaining shoulder on said clamp, and a 10 wedge between said shoulder and said flange.

4. In a rail anchor tie plate the combination of a tie plate having integral thrust sustaining abutment means engaging a base 15 flange of a rail, a rail clamp, a jaw on said clamp overlying the other base flange of the rail, an integral lug on said clamp having thrust sustaining engagement with said tie plate, and a thrust sustaining shoulder on 20 said clamp cooperating with the rail, a spike through said clamp and tie plate, and a wedge between said thrust sustaining shoulder and rail cooperating with said integral abutment means to prevent creeping of the 25 rail.

5. In a rail anchor tie plate the combina-

tion of a substantially rectangular plate having a portion bent up out of the body of the plate to form a permanent hook for overlying a base flange of a rail, a clamp in thrust 30 sustaining engagement with said tie plate, said clamp having a jaw overlying the other flange of the rail and a thrust sustaining shoulder cooperating with said last named flange, a spike driven through said clamp 35 and tie plate, and a wedge between said shoulder and said last named flange.

6. In a rail anchor tie plate the combination of a tie plate having an integral projection overlying the base flange of a rail, 40 and a wedge driven into position between said projection and the top of the rail flange.

7. In a rail anchor tie plate the combination of a tie plate having a hook portion 45 bent up out of the body of the plate and overlying the base flange of a rail, and a wedge driven into position between said hook portion and the top of the rail flange.

In witness whereof, I hereunto subscribe 50 my name this 31 day of March, 1925.

EMERY M. McVICKER.
